DESIGN FOR A SWIMMING SUIT

John O. Gantner, Jr., San Francisco, Calif.

Application February 24, 1947, Serial No. 137,100

Term of patent 14 years

(Cl. D3—17)

To all whom it may concern:

Be it known that I, John O. Gantner, Jr., a citizen of the United States, residing at 1036 Vallejo Street, in the city and county of San Francisco and State of California, have invented a new, original, and ornamental Design for Swimming Suits, of which the following is a specification, reference being had to the accompanying drawing, forming part thereof.

Fig. 1 is a front elevation of a swimming suit, showing my new design.

Fig. 2 is a back elevation of the suit shown in Fig. 1.

Fig. 3 is a side view of the suit shown in Fig. 1.

The shaded portion of the drawing is formed of a luminescent material in a color contrasting with the remainder of the suit.

I claim:

The ornamental design for a swimming suit, as shown and described.

JOHN O. GANTNER, JR.
